DESIGN FOR A TIRE

Kimball D. Smith, Akron, and Wilbur H. Adams, Cleveland, Ohio, assignors to The B. F. Goodrich Company, New York, N. Y., a corporation of New York

Application October 5, 1937, Serial No. 71,978

Term of patent 14 years

To all whom it may concern:

Be it known that we, Kimball D. Smith, a citizen of the United States, residing at Akron, in the county of Summit and State of Ohio, and Wilbur H. Adams, a citizen of the United States, residing at Cleveland, in the county of Cuyahoga and State of Ohio, have invented a new, original, and ornamental Design for a Tire, of which the following is a specification, reference being had to the accompanying drawing, forming a part thereof, of which:

Fig. 1 is a perspective view, partially in dotted lines, of a tire showing our new design.

Fig. 2 is a fragmentary plan view.

Fig. 3 is a section taken along the line 3—3 of Fig. 2.

We claim:

The ornamental design for a tire as shown.

KIMBALL D. SMITH.
WILBUR H. ADAMS.
